Inventor.

Euclid I. La Chapelle

UNITED STATES PATENT OFFICE.

EUCLID I. LA CHAPELLE, OF BROCKTON, MASSACHUSETTS.

SHOE-TURNING MACHINE.

Application filed March 27, 1920. Serial No. 369,311.

To all whom it may concern:

Be it known that I, EUCLID I. LA CHAPELLE, a citizen of the United States, residing in Brockton, county of Plymouth, Commonwealth of Massachusetts, have invented a certain new and useful Improvement in Shoe-Turning Machines, of which the following is a specification, reference being had to the drawings accompanying the same and forming a part thereof.

My present invention relates to shoe forepart turning machines and is herein shown as applied, for convenience only, to a shoe turning machine of the description shown in my patent for shoe turning machines, No. 1,336,750 issued April 13, 1920. The shoe turning elements therein shown, being transposed to the front of the machine frame in the present patent application, to lower same for the convenience of the operator, which feature is not, of course, patentable and which forms no part of my present invention.

My present invention relates to shoe turning machines that are provided with sole-clamping members and contemplates the improvement of such machines, but, I want it well understood that my invention does not relate solely to the sole-clamping members of such machines and that it may be embodied in some of the remainder of the shoe turning elements of shoe turning machines, when not embodied in the clamping members, and that the appended claims must be interpreted in that broad sense. Furthermore, my present invention is not an improvement upon the machine shown in my Patent No. 1,336,750 issued April 13, 1920; because it is preferable to hold a shoe sole directly with the hand, as described and claimed therein, and one of the advantages of so holding directly with the hand is that the operator may then feel any undue strain upon the shoe and may immediately release the shoe from the turning elements to immediately cause the straining action thereof to be terminated upon the toe-end of the shoe.

I, however, contemplate improving shoe forepart turning machines which are provided with sole-clamping members, for the reason that prior to my present invention,

some shoe forepart turning machines, provided with clamping members adapted to clamp the sole at its heel part and some shoe forepart turning machines, of later date, provided with clamping members adapted to clamp the sole at its shank part have been made, but have not, so far as I am aware, gone into practical use, particularly because of objection to the damage caused to the toe-end of the shoe by the shoe turning member being forced into the toe-end of the shoe too far, and especially so with machines that are power actuated, so as to punch out the toe-end to an extent sufficient to cause serious damage.

I improve such machines for the further reason that I intend introducing to the shoe making trade, by the introduction of my present invention, the making of special turn shoes having extra heavy leather soles, of corresponding heft, or of heavier heft as that of outsoles of women's heavy grade welt or McKay shoes, as now being made.

Such, special turn shoes may favorably compare to Goodyear welt shoes, notably in women's make, and such shoes may be properly turned by my novel shoe turning machine, herein disclosed. Women's turn shoes, as herein contemplated, are adapted to street wear and being lighter in weight and more flexible and cheaper to manufacture than Goodyear welt shoes and therefore comparatively cheaper in price to the consumer may be given the preference over Goodyear welt shoes, but, so far as I am aware, such shoes have never been made in the general run of shoe factories, because of the difficulty of turning the forepart by hand, or because of the objectionable feature of punching out the toe-end of the shoe by machine.

Such special turn shoes require, to be positively held against the strain of the forepart turning operation, sole-clamping members, such as herein disclosed, but, it is to be appreciated that although my present invention is intended for turning the forepart of such special shoes, it may be usefully employed for turning the forepart of turn shoes having ordinary soles, such as used in the making of turn shoes in the general run of shoe factories and the appended claims

must be so interpreted since the possibility of damage to the toe-end of shoes is always existent regardless of the kind of soles incorporated into the shoes.

5 The object of my present invention is to improve shoe forepart turning machines, that are provided with sole-clamping members, so that the possibility of damage to the toe-end by the shoe turning elements of 10 such machines is practically eliminated and I attain this object by a novel arrangement of the sole-clamping members illustrated in the accompanying drawings, in which:

15 Figs. 1 and 2 are respectively side and front elevations of a shoe turning machine embodying my invention.

20 Figs. 3 to 6 are detailed views illustrating the different steps in the turning operation of the heel part and forepart.

25 Fig. 7 illustrates a detail of the cross-head.

The complete machine is illustrated in Figs. 1 and 2 and comprises a base 10, having an upright support 12, mounted thereon and also a bearing 14, in which the main shaft 16, is journaled, said shaft having a driving pulley 18, on one end and a pinion 20, on the opposite end, the latter being arranged in mesh with a large gear 22, mounted 30 on a shaft 24, also journaled in a bearing on the base. The upright support 12, is provided with vertical guideways 26, in which a cross-head 28, is mounted to slide, and a connecting rod or link 30, is pivoted to said cross-head at one end and eccentrically connected to said gear 22, at the other end, so that as the gear is rotated said cross-head will be reciprocated.

35 A round bar 32, (which I hereafter term a turning member, as it corresponds in shape and function to the ordinary turning iron, generally employed in hand turning) is fixed to an arm extending from the support 12, in a vertical position, said turning member being provided with the usual friction roll 34, in its upper end, and a tubular cylindrical sleeve or plunger 36, is slidably mounted on said turning member 32, and is connected to the cross-head 28, so that said sleeve will be caused to reciprocate on the turning member 32, when the main shaft is driven. The upper end portion of said sleeve is tapered or beveled at its front side, forming a beveled face 40 and is provided 40 with a projection 42, at its rear side, the under side of said projection being corrugated or provided with teeth and a co-acting member 44, is pivoted to a shaft 46, said shaft extending through the cross-head 28, 45 which is slotted to receive the said co-acting clamping member 44, as shown at 28^a, Fig. 7, and a hand lever 50, is secured to the protruding end of the shaft 46, whereby the operator may control the clamping action 50 of said member 44, during the shoe forepart

turning operation and a spring 52 acts to move the member 44 out of operative position and against a pin 56, which limits its movement under the action of said spring.

55 This novel arrangement of clamping members permits the operator to immediately open the clamping members after the toe-end has been turned thereby and by the turning member 32, and thereby the damage to the toe-end of the shoe by the turning member 32, is overcome.

A bracket 58, is rigidly secured to the rear side of the support 12, and is extended upward and then downward in goose-neck form, the depending end thereof being provided with a heel turning cup 60, of common form, said cup being interchangeable to adapt the machine for shoes of different types, when the heel part and the forepart are turned by a single machine, as in the present case, and the said cup is held in inverted position directly over the sleeve 36, so that, when the latter is lifted, it will be passed into said cup adjacent its walls.

55 The operation is as follows:

60 While the sleeve 36, is being moved up, the operator places, with his left hand within the shoe forepart, the heel portion of the shoe on the cup 60, so that the rear part edge of the latter engages the seam which connects the shoe upper to the sole. The upper end of the sleeve 36, is shaped to correspond to the interior face of the cup, and as it moves upward it engages the sole-seam of the shoe and forces it inward, or breaks it, as commonly termed, and, during the latter portion of its upward movement, it will engage the sole of the shoe and will flatten the heel-seat against the bottom of the cup, which is preferably covered with rubber for that purpose, as indicated in Fig. 3, and thus the heel part of the shoe is turned in the ordinary manner, as indicated in Fig. 4. The sleeve then descends and during its downward movement, the operator presses the heel of the shoe downward and out of the cup with his right hand and slides it rearward on the upper end of the sleeve and then bends it over the end of the projection 42 and then the operator, holding the shoe over the end of the sleeve with his left hand still within the shoe forepart, moves the lever 50, forwardly with his right hand and the clamping member 44, is thereby set in engagement with the sole at its shank part and firmly clamps it against the projection 42. The operator, still having the left hand within the forepart of the shoe, spreads the shoe upper and bends the sole longitudinally around the sleeve 36. The sleeve is, meanwhile, descending and by this time will have been moved down until its upper end is below the level of the roll 34, so that the sole will then be engaged by said roll. The sole being held 65

positively with the projection 42, by the clamping member 44, and the operator's hand being within the forepart of the shoe, the sole is drawn over the roll by the clamping members, causing the forepart of the shoe to be turned, as shown in Fig. 6. To prevent damage to grain side of the shoe sole, I provide a rubber covering 48, for the sole engaging end of the clamping member 44.

I also provide a spring 52, for holding the clamping member 44, in opened position against the stop 56.

The forepart of the shoe may over slip to either side during the turning operation and an important and novel feature of my invention resides in the mounting of the member 44 loosely at 46 for adaptation to free movement of the said member relatively to the shoe in the machine and in the further arrangement and construction of the said member whereby the operator may directly move the same from and toward the shoe in the machine to disengage and re-engage the shoe during the shoe turning operation by the shoe turning instrumentalities under the influence of motive power actuating means, to enable the operator to properly replace the shoe forepart on the roll 34 of the shoe turning member 32 while the shoe is disengaged of the member 44 and is thereby released from strain on the roll 34.

I herein show and describe, power actuating means, a shoe forepart turning member and a heel turning cup (although a heel turning means does not form a part of and is not absolutely necessary to my present invention and is not claimed herein) and sole-clamping members adapted to engage the sole of a shoe at its shank part and the novelty of which consists in being so arranged that the operator may cause, during the time of the actuation of the power actuating means, their release of the sole immediately after the toe-end of the shoe has been turned thereby and by the shoe turning member under the influence of the power actuating means, so that the straining action of the shoe forepart turning elements, upon the toe-end of the shoe, is thereby immediately terminated and thus the objection to the damage caused to the toe-end of the shoe by the shoe turning member is overcome.

In turning by hand the forepart of all kinds of turn shoes, expert workmen engage the sole at its shank part, to avoid stretching and distorting the shank part of the sole as they pull upon the sole only in turning, to avoid stretching and distorting the shoe upper and its lining and the overstraining of the seam uniting the shoe upper and the sole.

I, therefore, show herein, a sole-clamping member adapted to co-act with an additional member, whereby the shank part of a turn

shoe sole may be clamped and positively held from movement therein during the time of the shoe fore-part turning operation, so that the strain of turning is practically all upon the sole.

It will be obvious that, while the machine herein described is especially designed and adapted for continuous actuation, it may be provided with a well known stop mechanism, so that it will come to a rest each time the sole-clamping members are moved to their lowest point. I do not, however, consider the incorporation of such means as either necessary or desirable, except in special cases, as the speed of the machine can usually be gauged to correspond to the rapidity with which the operator is able to perform his work.

I want it well understood that my invention and this patent are to be limited by the appended claims only and I claim and desire to secure by Letters Patent of the United States, protection for all the novelty herein disclosed to which I am entitled under the statutes, and the following claims are to be interpreted broadly to give effect to this intention.

Having thus described my invention, what I claim as new and desire to secure by Letters Patent of the United States is:

1. A shoe turning machine, having, in combination, a plurality of shoe turning elements comprising, a shoe forepart turning member and co-acting clamping members, adapted to engage the sole of a shoe at its shank part, and actuating means for at least one of said plurality of shoe turning elements, said shoe forepart turning member and said co-acting clamping members being so relatively positioned and arranged that the operator may cause disengagement of the shoe therefrom and may remove the shoe from the machine during the actuation of said actuating means.

2. A shoe turning machine, having, in combination, the elements recited in claim 1, and a spring to open said co-acting clamping members.

3. A shoe turning machine, having, in combination, a plurality of shoe turning elements comprising, a shoe forepart turning member and co-acting clamping members, adapted to engage the sole of a shoe, power actuating means for at least one of said shoe turning elements, said co-acting clamping members being so arranged that the operator may close same upon the sole of the shoe and hold same in closed condition thereon during the shoe turning operation by said plurality of shoe turning elements under the influence of said power actuating means, and means to move said co-acting clamping members apart only.

4. A shoe turning machine, having, in combination, a plurality of shoe turning

- members, actuating means for at least one of said plurality of shoe turning members, some of said plurality of shoe turning members being arranged for movement and being 5 adapted to engage the shoe at its heel portion and hold the shoe against the strain of the shoe turning operation by said plurality of shoe turning members, means, under control of the operator, whereby the shoe 10 turning operation may be terminated independently of said actuating means, and moving means for moving said some of the plurality of shoe turning members in one direction only.
- 15 5. A shoe turning machine, having, in combination, a plurality of shoe turning members, actuating means for at least one of said plurality of shoe turning members, some of said plurality of shoe turning members, being arranged for movement and being 20 adapted to engage the sole of the shoe and hold the shoe against the strain of the shoe turning operation by said plurality of shoe turning members, means, under control 25 of the operator, whereby the shoe turning operation may be terminated independently of said actuating means and a spring for moving said some of the plurality of shoe turning members in one direction only.
- 30 6. A shoe turning machine, having, in combination, a plurality of shoe turning members, actuating means for at least one of said plurality of shoe turning members, some of said plurality of shoe turning members, being arranged for movement and being 35 adapted to engage the shoe at its heel portion and hold the shoe against the strain of the shoe turning operation by said plurality of shoe turning members, means, under control 40 of the operator, whereby the shoe turning operation may be terminated independently of said actuating means and a spring for moving said some of the plurality of shoe turning members in one direction only.
- 45 7. A shoe turning machine, having, in combination, a plurality of shoe forepart turning elements, actuating means for at least one of said plurality of shoe forepart turning elements, some of said plurality of shoe forepart turning elements being adapted 50 to engage the rearpart of a shoe to thereby cause the shoe to be held against the strain of the turning operation and being loosely mounted for free movement toward and from the shoe applied to the machine, and moving means therefor, whereby the operator may directly freely move the same from the rearpart of the shoe independently 55 of said actuating means and whereby the operator may directly freely move the same toward the rearpart of the shoe independently 60 of said actuating means to cause release and re-engagement of the shoe by said some of said plurality of shoe forepart turn- 65 ing elements during the actuation of said actuating means.
8. A shoe turning machine, having, in combination, a plurality of shoe forepart turning elements and actuating means for at least one of said plurality of shoe forepart turning elements and some of said plurality of shoe forepart turning elements being adapted to engage the rearpart of a shoe to thereby cause the shoe to be held 70 against the strain of the turning operation and being loosely mounted for free movement toward and from the shoe to permit the operator to directly freely move the same from the rearpart of the shoe independently 75 of said actuating means to thereby cause immediate termination of the straining action of said plurality of shoe forepart turning elements upon the extreme toe-end of the shoe and thus terminate the shoe forepart turning operation during the actuation 80 of said actuating means.
9. A shoe turning machine, having, in combination, the turning member 32, the sleeve 36, the projection 42, the connecting rod 30, the gear 22, the driving pulley 18, the co-acting member 44, the cross-head 28, and the shaft 46 for holding said co-acting member 44, loosely mounted on said cross-head 28, to permit the operator to directly 85 freely move the said co-acting member 44, toward and from the shoe applied to the machine during the actuation of said gear 22, by said driving pulley 18, for the purposes described. 90
10. A shoe turning machine, having, in combination, a plurality of shoe turning elements comprising, a shoe forepart turning member and co-acting clamping members adapted to engage the rearpart of a shoe, and actuating means for at least one of said plurality of shoe turning elements, and said shoe forepart turning member and said co-acting clamping members being so relatively 95 positioned and arranged that the operator may apply a shoe to the machine during the actuation of said actuating means. 100
11. A shoe turning machine, having in combination, a plurality of shoe turning elements comprising, a shoe forepart turning member and co-acting clamping members adapted to engage the rearpart of a shoe, and actuating means for at least one of said plurality of shoe turning elements, and said shoe forepart turning member and said co-acting clamping members being so relatively positioned and arranged that the operator may cause disengagement of the shoe therefrom and may remove the shoe 110 from the machine during the actuation of said actuating means. 115
12. A shoe turning machine, having, in combination, a plurality of shoe forepart turning elements and actuating means for 120 some of said plurality of shoe forepart turn- 125

at least one of said plurality of shoe forepart turning elements, some of said plurality of shoe forepart turning elements being adapted to engage the rearpart of a shoe to thereby cause the shoe to be held against the strain of the turning operation, and said plurality of shoe forepart turning elements being so relatively positioned and arranged that the operator may apply a shoe to the machine during the actuation of said actuating means.

13. A shoe turning machine, having, in combination, a plurality of shoe forepart turning elements and actuating means for at least one of said plurality of shoe forepart turning elements, some of said plurality of shoe forepart turning elements being adapted to engage the rearpart of a shoe to thereby cause the shoe to be held against the strain of the turning operation, and said plurality of shoe forepart turning elements being so relatively positioned and arranged that the operator may cause disengagement of the shoe therefrom and may remove the shoe from the machine during the actuation of said actuating means.

14. A shoe turning machine, having, in combination, a plurality of shoe forepart turning elements and continuous actuating means for at least one of said plurality of shoe forepart turning elements, some of said plurality of shoe forepart turning elements being adapted to engage the rearpart of a shoe to thereby cause the shoe to be held against the strain of the turning operation, and said plurality of shoe forepart turning elements being so relatively positioned and arranged that the operator may cause disengagement of the shoe therefrom and may remove the shoe from the machine during the actuation of said actuating means.

15. A shoe turning machine, having, in combination, a plurality of shoe forepart turning elements and actuating means for at least one of said plurality of shoe forepart turning elements and some of said plurality of shoe forepart turning elements being adapted to engage the rearpart of a shoe to thereby cause the shoe to be held against the strain of the turning operation and being loosely mounted for free movement relatively to the shoe applied to the machine and being arranged and so built that the operator may directly freely move the same relatively to the shoe applied to the machine, for the purposes described.

16. A shoe turning machine, having, in combination, a turning member adapted to engage the forepart of a shoe and co-acting clamping members adapted to engage the rearpart of the shoe, all said members being so relatively positioned and arranged that the operator may directly terminate their co-operation.

17. A shoe turning machine, having, in combination, a turning member adapted to engage the forepart of a shoe and co-acting clamping members adapted to engage the rearpart of the shoe, all said members being so relatively positioned and arranged that the operator may directly operate one of said co-acting clamping members to engage and disengage the shoe.

18. A shoe turning machine, having, in combination, a plurality of shoe forepart turning elements and actuating means for at least one of said plurality of shoe forepart turning elements, and some of said plurality of shoe forepart turning elements being adapted to engage the rearpart of a shoe to thereby cause the shoe to be held against the strain of the turning operation and being loosely mounted for free movement relatively to the shoe applied to the machine and being arranged for operation, in co-operation with the remainder of said plurality of shoe forepart turning elements to turn the shoe, independently of said actuating means at all times.

19. A shoe turning machine, having, in combination, a shoe forepart turning member, co-acting clamping members, adapted to engage the rearpart of a shoe to thereby cause the shoe to be held against the strain of the shoe turning operation and actuating means for some of said members, and one of said co-acting clamping members being loosely mounted for free movement relatively to the shoe applied to the machine and being arranged for operation, in co-operation with the remainder of said members to turn the shoe, independently of said actuating means at all times.

20. A shoe turning machine, having, in combination, a plurality of shoe forepart turning elements and power actuating means for at least one of said plurality of shoe forepart turning elements and some of said plurality of shoe forepart turning elements being adapted to engage the rearpart of a shoe to thereby cause the shoe to be held against the strain of the turning operation by said plurality of shoe forepart turning elements under the influence of said power actuating means and being arranged for free movement relatively to the shoe applied to the machine to permit the operator to cause immediate termination of the shoe turning operation independently of said power actuating means and being arranged for operation, in co-operation with the remainder of said plurality of shoe forepart turning elements to turn the shoe, independently of said power actuating means at all times.

21. A shoe turning machine, having, in combination, a plurality of shoe forepart turning elements and actuating means for at least one of said plurality of shoe fore-

part turning elements and some of said plurality of shoe forepart turning elements being adapted to engage the rearpart of a shoe to thereby cause the shoe to be held against the strain of the shoe turning operation and being loosely mounted for free movement relatively to the shoe applied to the machine and being so arranged that the operator may directly freely move the same from the rearpart of the shoe independently of said actuating means and being so arranged that the operator may directly freely move the same toward the rearpart of the shoe independently of said actuating means to thereby cause release and re-engagement of the shoe by said some of said plurality of shoe forepart turning elements during the actuation of said actuating means.

22. A shoe turning machine, having, in combination, a plurality of shoe forepart turning elements and power actuating means for some of said plurality of shoe forepart turning elements, and some of said plurality of shoe forepart turning elements being so arranged that the operator may directly hold the same toward the shoe applied to the machine during the time of the shoe turning operation by said plurality of shoe forepart turning elements to thereby cause the shoe to be held against the strain of the shoe turning operation and to thereby permit the operator to control the duration of the shoe turning operation by said some of said plurality of shoe forepart turning elements under the influence of said power actuating means.

23. A shoe turning machine, having, in combination, a plurality of shoe forepart turning elements and actuating means for at least one of said plurality of shoe forepart turning elements, and some of said plurality of shoe forepart turning elements being adapted to engage the rearpart of a shoe to thereby cause the shoe to be held against the strain of the shoe turning operation and being arranged for movement toward the shoe independently of said actuating means at all times and being loosely mounted for free movement relatively to the shoe to permit the operator to directly freely move the same from the shoe independently of said actuating means to thereby cause immediate termination of the straining action of said plurality of shoe forepart turning elements upon the extreme toe-end of the shoe and thus terminate the shoe forepart turning operation during the actuation of said actuating means.

24. A shoe turning machine, having, in combination, a plurality of shoe forepart turning elements and power actuating means for at least one of said plurality of shoe forepart turning elements, and some of said plurality of shoe forepart turning elements being adapted to engage the rearpart of a

shoe to thereby cause the shoe to be held against the strain of the shoe turning operation and being mounted for movement toward the shoe independently of said power actuating means at all times and said plurality of shoe forepart turning elements being so relatively positioned and arranged that the operator may apply a shoe to the machine during the actuation of said power actuating means.

25. A shoe turning machine, having, in combination, a plurality of shoe forepart turning elements, actuating means for at least one of said plurality of shoe forepart turning elements, and some of said plurality of shoe forepart turning elements being loosely mounted for free movement relatively to the shoe applied to the machine independently of said actuating means during the time of the turning of the toe part by said plurality of shoe forepart turning elements under the influence of said actuating means, and being so arranged relatively to the remainder of said plurality of shoe forepart turning elements that the shoe may be thereby held against the strain of the turning of its toe part independently of said actuating means during the time of the turning of its toe part by said plurality of shoe forepart turning elements under the influence of said actuating means, to thereby permit the operator to control the duration of the shoe turning operation independently of said actuating means, and moving means, whereby said some of said plurality of shoe forepart turning elements may be moved toward the shoe applied to the machine.

26. A shoe turning machine, having, in combination, a plurality of shoe forepart turning elements and actuating means for at least one of said plurality of shoe forepart turning elements, and some of said plurality of shoe forepart turning elements loosely mounted for free movement relatively to the shoe applied to the machine independently of said actuating means during the time of the turning of the toe part by said plurality of shoe forepart turning elements under the influence of said actuating means, and being so arranged relatively to the remainder of said plurality of shoe forepart turning elements that the shoe may be thereby held against the strain of the turning of its toe part independently of said actuating means during the time of the turning of its toe part by said plurality of shoe forepart turning elements under the influence of said actuating means, to thereby permit the operator to control the duration of the shoe turning operation independently of said actuating means.

27. A shoe turning machine, having, in combination, a plurality of shoe forepart turning elements, actuating means for at least one of said plurality of shoe forepart

turning elements, some of said plurality of shoe forepart turning elements being arranged for movement and being adapted to hold a shoe against the strain of the turning operation, and moving means, arranged for moving said some of said plurality of shoe forepart turning elements in one direction only and arranged for co-operation

with said some of said plurality of shoe forepart turning elements in the releasing of the shoe from over strain at its toe-end during the actuation of said actuating means.

In testimony whereof, I have signed my name to this specification.

EUCLID I. LA CHAPELLE.
